Patented Aug. 27, 1918.

UNITED STATES PATENT OFFICE.

EDWARD O'TOOLE, OF GARY, WEST VIRGINIA.

SYSTEM OF MINING COAL.

1,276,952.

Specification of Letters Patent. Patented Aug. 27, 1918.

Application filed March 16, 1914. Serial No. 824,979.

To all whom it may concern:

Be it known that I, EDWARD O'TOOLE, a citizen of the United States, residing at Gary, in the county of McDowell and State 5 of West Virginia, have invented a new and useful System of Mining Coal, of which the following is a specification.

My invention has relation to mining, and more particularly to mining coal, and one 10 object of the invention is to provide a novel system of mining whereby the maximum capacity of the mine is reached in the shortest possible time, a material reduction in the amount of the investment necessary to put 15 the mine upon a paying basis is effected, and the cost of mining is lessened.

Another object of my invention is to provide an improved mining system by which the mine is maintained at its maximum 20 capacity for the longest possible time interval while the removal of coal from the mine continues.

A further object of the invention is to provide a novel system of mining in the use of 25 which the mine is efficiently ventilated, the safety of the employees is obtained, and liability of injury to the workmen and damage to the mine is overcome and prevented.

A still further object of the invention is 30 to provide an improved system of mining in which the coal handling operations are facilitated, the coal is removed with increased rapidity, and the cost of removing the mined coal is lessened.

Still further objects of the invention will 35 become apparent hereinafter in the specification and appended claims.

The drawing forming part of this specification, is a sectional plan showing the preferred manner of forming the mine and removing the coal or other material being 40 mined in accordance with my improved system.

This novel system of mining is adapted 45 for use with either a shaft or a drift mine, the type of mine depending upon the topography of the country and the depth of the coal seam below the ground level.

In forming and operating a mine in accordance 50 with my improved system of mining, the location of the entrance to the mine relative to the boundaries of the coal body to be mined is first determined. In determining the position of the mine entrance,

the type of mine, the topography of the 55 surrounding country, the location of side tracks leading to the railroad on which the coal is transported, and the depth of the coal seam and other local conditions form governing factors. 60

In starting the mine, a series of airways 21, 22, 23, 24, 25 and 26 are started, from the bottom of the shaft when a shaft is necessary or desirable, and from the surface of the ground otherwise, these airways extending 65 in parallel lines and, usually, in a direction parallel to a line defining one side of the coal body, property line or section line.

When the airways have been driven a sufficient distance the first heading is turned 70 out of the airways, this heading comprising a plurality of entries 31, 32 and 33 which extend lengthwise at an angle to the length of the airways. The heading is located at a considerable distance from one end of the 75 coal bed or boundary line of the coal field, so as to divide the coal on one side thereof into a section.

The entry 31 is turned out of the return airway 25, the entry 32 out of the airway 80 24, and the entry 33 is connected by the cross entry 34 to each of the intake airways 21, 22 and 23, and return airways 24, 25 and 26. The intake and return airways are being constantly driven after being started, 85 and the entries 31, 32 and 33 forming the first heading also are continuously driven after being turned out of the airways.

Cross entries 35, 36, are formed between the entries 31, 32, 33 at intervals in the 90 length of the heading to connect the entries forming the heading and preferably the cross entries 35 are staggered relative to the cross entries 36.

As soon as the first heading, formed by 95 the entries 31, 32, and 33, is driven a sufficient distance, a room 41 is turned out of the entry 31, this room extending lengthwise at an angle to the length of the heading, and being driven as fast as may be until it reaches the butt-off 40, or end of the coal seam, property or section line. 100

While the room 41 is being driven the first heading is also being increased in length, and upon its reaching a point at a 105 suitable distance from the room 41, a second room 42 is turned out of the heading and is driven lengthwise parallel to the room 41.

until the butt-off 40 is reached. The coal is removed from between the rooms 41, 42, at intervals in the length of the rooms 41 to provide a series of cross-entries connecting these rooms and to form a series of supporting pillars for the roof of these rooms. A succession of rooms 43, 44, 45, etc., are turned out of the entry 31 of the heading as fast as the heading reaches a suitable depth.

10 The distance between the rooms will vary and will be regulated by the thickness of the overlying strata, the thickness and composition of the different layers of stratified rock, inclination of the coal seam, the hardness and crushing strength of the coal, and the width of the rooms being turned, as well as local conditions, but generally will be turned on centers of about 70 feet. The number of rooms of course may vary considerably depending upon the size of the coal field.

20 The first heading (which is formed by the entries 31, 32, 33,) will be extended at a substantially uniform speed and the rooms 41, 42, 43, etc., will also be extended at a substantially uniform speed, so that each room will reach the butt-off 40 about the same distance in advance of the following or next turned room as it was driven when the next 30 turned room was started.

30 Car tracks of the usual construction for the coal are laid in the airways 24 and 25 as the airways are formed, and turnouts connect the tracks in the airways 24, 25 with similar tracks which are laid in the entries 31 and 32 of the first heading, as the heading is driven. A turn-out from the tracks in the entry 31 connects with the track laid in each room as the room is turned out of the 40 heading, and the tracks are extended as the rooms are driven.

40 The use of the entry 32 is discontinued as soon as it has advanced far enough to connect with the haulage way 81 from the second heading formed by the entries 71, 72 and 73 and the remaining entries 31 and 33 are extended continuously and as rapidly as possible until the opposite end of the coal seam or the property line, as the case may be is reached. Additional rooms 43, 44, 45, 46, etc., are successively turned out on the entry 31 of the first heading as fast as the location for each room is reached by the advancing end of the heading, so that in 50 this way coal is being continuously mined, not only in the heading, but in a constantly increasing number of rooms, the number of rooms working and the capacity of the heading reaching a maximum soon after starting and continuing at the maximum until the heading reaches the aforesaid end of the coal seam or property line. The number of rooms will depend upon the length of the coal body, and the distance between 60 the rooms,

75 As soon as the first started room 41 reaches the butt-off 40, the removal of the pillars between the adjoining rooms is commenced, progressing from the inner end of the room 41 toward its outer end or mouth, 70 the room being robbed of the coal in the pillars and any timbering placed during driving of the room being removed so as to permit the roof to fall as the robbing is completed.

75 The rooms 42, 43, etc., will in turn reach the butt-off 40, successively in the order in which they are started and as soon as the butt-off is reached in each room, robbing of the pillars is commenced, in this way a constantly increasing quantity of coal is being mined until the maximum output of the heading or section is reached.

80 When this occurs the maximum coal output will be maintained until the last room at the extreme end of the first heading is completed, after which in this section of the mine, the quantity of coal will gradually become less, while robbing the last formed room is being effected.

85 The airways, first heading and the rooms turned out of this heading are continuously advanced and are driven as rapidly as possible after being started. When the airways 21, 22 and 23, 24, 25 and 26 have been advanced for a sufficient distance, and the first heading or heading formed by the entries 31, 32 and 33 has progressed to a sufficient extent, a second heading formed by the entries 71, 72 and 73, which parallel the first 90 formed heading, is turned, the entry 71 connecting into the airways 23 and 26, the entry 72 into the airways 24, 25 and 26 and the entry 73 into the airway 26. Cross entries 74 and 75 are cut at intervals in its length, 95 as the second heading is driven, to connect the entries 71, 72 and 73, these cross entries also being relatively staggered in the same manner as the cross entries 33, 36.

100 After the second heading is driven for a short distance, a haulway 81 is started from the entry 71 forming part of this heading and also at the same time from the entry 33 of the first heading it being caused to substantially parallel lengthwise to that of the 105 first formed rooms 41, 42, etc.

110 By the time the first formed rooms 41, 42, 43, etc., have advanced to the butt-off 40 and robbing of the supporting pillars between these rooms has removed all of the coal and, 115 in retreating the first heading has been reached by the robbing line, the entries 71, 72 and 73 forming the second heading will be connected to the first heading by the haulways 81, 82 and 83 and the tracks, which are 120 laid as the headways and haulways advance, will be connected so as to afford means for hauling the coal then being mined and delivered from the rooms 41, etc., in the first heading out of this heading through the 125 130

haulways 81, 82, 83 into the entry 71 of the second heading and through the second heading into the airway 25.

As the second heading advances, haulways 82, 83, etc., will be driven and tracks laid therein, to connect the headings at separated intervals in the length of the headings, so that, as robbing of the pillars in the first completed rooms progresses and the first formed heading becomes destroyed or its roof becomes unsafe, and also, as required, by the development of the second heading so as to not interfere with the workings, means of communication between the headings for the removal of the coal are maintained at successively greater distances from the airways or mouth of the headings.

As by the time the first driven rooms 41, 42, etc., are robbed, the haulway 81 connecting the first and second headings will have been completed, and the necessity for having the entry 32 ends, so that for the remaining depth of the first heading, but two entries 31 and 33 will be formed, the entry 31 for the mine car tracks and the entry 33 principally to insure an adequate circulation of air while developing.

When robbing of the rooms 41, 42, 43, etc., has advanced to the mouth of the room 30 opening into the entry 31 of the first heading, robbing of the pillars between the entries 31 and 32 is started and in due time the pillars between the entries 32 and 33.

This robbing of the pillars renders the 35 heading formed by the entries 31, 32 and 33 unsafe or unfit for use, but in the meantime the second heading formed by the entries 71, 72 and 73 will have advanced a sufficient distance to permit the haulways 40 80, 81, 82 and 83 to be completed, and the removal of loaded coal cars and their replacement by empty cars will be effected through the haulways 81, 82, and 83, and the entries 71 and 72 into the airways 24 45 and 25 without interruption of the mining operations or reduction in the coal output.

When the entries 71, 72 and 73 forming the second heading have progressed a sufficient distance, the rooms 91, 92, 93, etc., will 50 be successively turned from the entry 71 and caused to extend parallel to the rooms 41, 42 and 43, at such a time that the first of these rooms will have advanced to the entry 33 of the first heading by the time the 55 robbing of the pillars in the rooms 43, 44, 45 and 46 and of the entries 31, 32, 33 has advanced to the same point. Robbing of the room 91 and successively 92 and 93 will then commence and continue in the same 60 robbing line as formed by the robbing of the rooms 41, 42, etc., off the heading 31.

When the time arrives in which the rooms 91, 92, 93, etc., turned from the second heading, are so advanced that hauling the loaded 65 cars through the entry 71 interferes with

the mining operations in this heading, a third heading formed by the entries 101, 102, 103 and 104, will have been turned from the airways and will have been advanced sufficiently to enable the haulways 115 and 116 70 to be formed so as to connect the third with the second heading.

In the same manner additional haulways 75 will be driven as required by the development of the headings from the entries forming the third heading to those of the second, but no rooms will be driven from the third heading until the first and second headings have been entirely robbed out, (i. e. all of the coal has been removed.) When this 80 third heading reaches the property line, the rooms will be turned and robbed, being robbed in retreating as in the ordinary practice.

In hauling the mined coal the miners 85 will deliver the loaded cars on the track extending through the entry 31 of the first formed heading, which is nearest the series of rooms. After a considerable number of rooms 41, 42, 43, etc., have been formed the 90 motor will enter the heading from the airway 25 with a trailing string of empty cars. The motor will push the loaded cars in front of it as it advances into the heading, collecting and coupling the loaded cars into a 95 train. As the motor proceeds into the heading, empty cars will be placed in front of each of the rooms being worked.

When the motor reaches a point beyond the haulway 81, all of the empty cars pulled 100 into the mine by it will have been dropped. The loaded cars in front of the motor having been coupled together to form a train, are then hauled out of the mine through the entry 32, so as not to interfere with the 105 empties just placed.

The next trip of the motor or a second motor will bring its trip of empties into the mine through the entry 31 and distribute them as described above in the entry 31 110 between the haulways 81 and 82, pushing the loaded cars ahead of it past the haulway 81. The motor will then pull its train of loaded cars through the haulway 81 to the second heading and out through the 115 entry 72 of this heading to the airways.

The next train of empties will go into the entry 31, pushing the loaded cars ahead of it and distributing the empties between the haulways 81 and 82, and hauling the 120 loaded cars through the haulway 82 to the second heading, and through the haulway 116 to the third heading and thence by the entry 101 of the third heading to the airways.

The next succeeding motor will haul its 125 trip or train of empties through the entry 31 as before described, pushing the loaded cars ahead of it and distributing the empties between the haulways 82 and 83, and will 130

then haul the trip of loaded cars through the haulway 86, and the second and third headings in the same manner as heretofore described, and in this way the heritage of the loaded cars not interfering with placing the empty cars with reference to the rooms being worked.

When the entries 81 and 82 are rendered unsafe by reason of robbing the pillars 42, 43, 44, etc., the motor will bring the empty cars into the mine through the entry 71 or the second heading, and haulway 81 and similarly, when this is made unsafe by robbing, the empties will be brought into the mine through the entry 101 of the third heading and thence by the haulway 113 to the second heading and by the haulway 82 to the first heading.

The coal mined from the second heading 20 will be mined in the same way as the coal from the first heading, using the haulways 113, 114, etc., to haul the coal to the entries 101 and 102 of the third set of headings so as to avoid interfering with the mining operations. This system will be continued in this way until the boundary of the property is reached, successive headings being turned from the airways and connected by haulways as has been described.

Robbing of the coal between the entries 81 and 83, and between 71, 72 and 73 will not interfere with this method of working, since the entries 101, 102, 103 and 104 forming the third heading will have only haulways turned on it until the section between the butt-off 40 and the first heading and, in succession, the section between the first and second headings are entirely "robbed out."

Beyond the third heading, the above described operations are then repeated and another section formed, headings being turned from the constantly advancing airways, rooms being successively turned from the headings, the rooms being robbed to remove the coal forming the supporting pillars, and the haulways being successively formed as required and abandoned as necessary caused by the removal of the coal demands, until the coal has been entirely re-

moved from the field, the number of the headings formed depending only upon the extent of the deposit of coal.

The advantages of my improved system will be apparent to those skilled in the art. By mining coal in accordance with my improved system the maximum capacity of the mine is quickly reached, the cost of starting the mine and bringing it up to its capacity is lessened, and the maximum capacity of the mine is maintained for the longest possible time.

The headings and haulways afford efficient means for handling the coal cars, and for ventilating the mine, so that the mine is operated in an economical and safe manner.

Variations in the system may be made without departing from my invention as defined in the appended claims.

I claim:

1. The system of mining coal consisting in driving an airway at the level of the coal seam, turning a heading out of the airway, successively turning a series of rooms out of the heading as the development of the headings progresses, turning a second heading out of the airway, turning a series of rooms out of the second heading, connecting the headings with a haulway at intervals in the length thereof and robbing the mine by removing the pillars therefrom in the order in which the rooms are driven.

2. The system of mining coal consisting in driving a plurality of airways at the level of the coal seam, turning headings out of the airways, successively turning a series of rooms out of each heading as the development thereof progresses, connecting the headings with a haulway at intervals in the length thereof, and robbing the mine by removing the pillars from the rooms in the order in which the rooms are driven.

In testimony whereof I have hereunto set my hand.

EDWARD O'TOOLE.
